DETACHABLE SASH

Joseph F. Kupec, Lincoln, Nebr.

Application December 17, 1934, Serial No. 757,895

2 Claims. (Cl. 16—128)

This invention relates to an improvement in windows and more particularly to the mounting of window sash in the window casings and control of the sash.

5 Since storm sash and screen sash are usually mounted interchangeably in window casings, the changing depending upon cold or hot seasons, it is an important feature to provide such an arrangement of parts that these changes may be conveniently made.

10 By use of the herein described invention the mounting of sash in window casings or removal therefrom may be readily and safely accomplished from the inside of a building, no outside work being required, this feature being of great advantage for use in tall buildings since the work may be performed speedily, conveniently and accidental injuries may be avoided.

15 The invention consists of the new and useful 20 construction, combination and arrangement of parts as described herein and claimed, and as shown in the drawings, it being understood that changes may be made in form, size, proportion of parts and minor details, said changes being 25 within the scope of the invention as claimed.

In the accompanying drawings, Fig. 1 is a broken away detail view showing the inner side of a detachable storm or screen sash provided with an arcuate guide-plate.

30 Fig. 2 is a detail view showing a roller bracket attached to the blind-stop of a window casing, the roller being in section.

Fig. 3 shows the outer side of a window casing, and windows therein.

35 Fig. 4 shows a window casing and storm sash in longitudinal section to illustrate the operation of hoisting the sash into operative position from the inner part of a building.

Fig. 5 is an enlarged detail relating to Fig. 4, 40 showing the upper part of the sash in its inclined position, the fastening devices being in section.

Fig. 6 is a view in detail relating to Fig. 5, 45 showing a socket-plate mounted on the vertical blind-stop of the window casing.

Fig. 7 is a view of the socket-plate and blind-stop taken at right-angles to the view shown in Fig. 6.

Fig. 8 is a detail showing the lower part of a 50 storm sash in section to clearly show a catch-member and a second catch-member mounted thereon.

Fig. 9 is a plan view showing a part of the 55 base of a window casing provided with a hinge and a latch pivotally mounted on the hinge,

movable for locking the sash in closed position and movable for maintaining the sash in open position, a part of a sash being added.

Referring now to the drawings for a more particular description, the invention is shown and described in connection with the base 10 and blind-stop 11 of a window casing 12, and a detachable storm sash 13, and pair of windows x.

While a detachable storm sash is shown in the drawings, it will be understood that the invention includes a detachable screen sash, the parts to be described for the control and mounting being the same so that one kind of sash may be substituted for the other conveniently whenever required.

In order that the objects first mentioned may be attained I provide a pair of downwardly projecting, rectilinear socket-plates 14, these being secured upon the inner sides of the casing near the top thereof, said sockets preferably being mounted upon the blind-stops 11 of the casing.

Each socket-plate 14 is provided with a slot 15 and includes a buffer-flange a disposed at right-angles to its base.

Numerals 16 indicate a pair of opposed, upwardly projecting, arcuate guide-plates which are secured to the upper end of the detachable sash 13, each arcuate guide-plate being provided with a slot 17.

Numeral 18 (Fig. 2) indicates a roller-bracket 30 which is secured to the upper part of the casing upon the blind-stop 11, said roller-bracket being used for supporting a hoisting-strand 19 for use when the sash is lifted to operative position or lowered therefrom.

Numeral 20 indicates a catch-member provided with a horizontal, apertured projection b, best shown in Figs. 8 and 9 of the drawings and at 21 is indicated a second catch-member, these parts being mounted on the lower end of the 40 sash upon the inner side thereof.

As thus described the hoisting of a window sash into operative position from within a building may be conveniently accomplished. The strand 19 is secured to the apertured projection 45 b at the lower end of the sash and engages in a staple 22 at top of the sash, and the strand engages the roller of the bracket 18 so that the sash may be elevated or lowered by manual use of said strand.

When moved through the casing to be fitted therein as shown in Fig. 4, the pair of arcuate guide-plates 16 will slide into the pair of sockets 14 of the casing, and by use of keepers 23 which engage in the apertures or slots 15 and 17 of the 55

respective sockets and guide-plates the sash may be supported by the casing, and it is obvious that the guide-plates 16 will readily slide downward from the sockets for removal of the sash 5 after the keepers 23 have been removed.

The operation of parts last mentioned will be readily understood by an inspection of Fig. 5 of the drawings, and it will be seen that on account of the arcuate form of the guide-plate 16 the storm 10 sash 13 may be swung outwardly of the casing, this being of advantage to provide ventilation of a building.

Since these members 16 are of arcuate form they may swing around the rectilinear socket-15 plates while the sash has a swinging movement to closed or open positions, the slots which are traversed by the keepers 23 also permitting the swinging movements of the window sash.

Numeral 24 (Figs. 3, 9) indicates a hinge which 20 is mounted on the base 10 of the window casing, and pivotally mounted at 25 upon one of the wings of the hinge 24 is a latch 26 having a terminal part bent at right-angles to provide a second latch-member 27 having a notch 28 opening on 25 its edge.

After the sash has been swung to closed position within the casing as shown in Fig. 9, the latch 26 may be swung downwardly into the catch 20 for locking the sash in closed position, the 30 latch 26, for this purpose swinging from its pivot 25 on a wing of the hinge 24.

In order to maintain a storm sash 13 in open position the latch 26 is also used and may be swung outwardly to the position shown in broken 35 lines in Fig. 9, the notch 28 of the second latch 27 of said latch 26 receiving the second catch 21 of the sash.

The latch 26 may have swinging movements in 40 a plane parallel with the longitudinal axis of the hinge for engaging the catch 20, and may be

swung at right-angles to said axis of said hinge outwardly of the window casing to permit said notch 28 to receive the second catch 21 of the sash, said latch 26 having two movements, one being parallel with the sash 13, and the other movement 5 being transverse to said sash to cause the second latch 27 to engage the second catch 21.

Since screen frames are generally fitted into the casing to remain in stationary position the use of keepers 23 will not be required, but will of 10 course be required in all instances when the sash is disposed in inclined position.

I claim as my invention,—

1. In a hinge for use with a sash and a stationary frame, a slotted socket-plate adapted to 15 be secured to the frame, a guide-plate adapted to be secured to the sash and having a slotted arcuate part, said sash being adapted to be fitted into the frame with the slot of said arcuate part in register with the slot of the socket-plate, a pivot 20 disposed at approximately right-angles to the face of the guide-plate engaging in said slots and adapted to be mounted in the sash for supporting and permitting a swinging movement of said sash relative to the frame.

2. In a hinge for use with a sash and a stationary frame, a rectilinear, vertically disposed socket-plate adapted to be secured to the frame, a guide-plate disposed parallel with the sash and adapted to be secured thereto and having a slotted 30 arcuate terminal part, said sash being adapted to be fitted into the frame with the slot of said arcuate terminal part in register with the slot of the socket-plate, a pivot disposed in said slots and adapted to be secured to the sash for supporting 35 said sash, whereby the arcuate part of the guide-plate may move around the lower end of the socket-plate to permit a swinging movement of said sash relative to the frame.

JOSEPH F. KUPEC. 40
